UNITED STATES PATENT OFFICE.

CHANNING E. LAW AND LORENZO C. LAW, OF DENVER, COLORADO.

ELECTRIC SWITCH.

1,277,609.

Specification of Letters Patent. Patented Sept. 3, 1918.

Application filed August 31, 1916. Serial No. 117,878.

To all whom it may concern:

Be it known that we, CHANNING E. LAW and LORENZO C. LAW, citizens of the United States, residing in the city and county of Denver and State of Colorado, have invented certain new and useful Improvements in Electric Switches; and we do declare the following to be a full, clear, and exact description of the invention, such as will enable others skilled in the art to which it pertains to make and use the same, reference being had to the accompanying drawings, and to the characters of reference marked thereon, which form a part of this specification.

This invention relates to switches to be used with electrically operated signaling devices for automobiles which indicate the direction of a turn or that the machine is about to stop.

The object is to furnish a switch that will readily control the signaling device as well as control the horn.

The invention is fully set forth in the following specification, illustrated in the accompanying drawings and more particularly pointed out in the appended claims.

In the drawings:

Figure 1 is a rear elevation showing an automobile with a signaling device with which the present invention is used.

Fig. 2 is a diagrammatic view showing the electrical connections for the several parts.

Fig. 3 is a plan view of the switch box with operating lever extending therefrom.

Fig. 4 is a similar view with the top plate or cover removed.

Fig. 5 is a horizontal section taken on approximately the lines 8—8, Fig. 6, with parts omitted.

Fig. 6 is a transverse section taken on line 9—9 of Fig. 4.

In Fig. 1 a signaling casing 5 is shown attached to the machine and having openings A and B and a centrally disposed opening T for the tail lamp. Three lamps 18, 19 and 20 are provided at one end to light up the three points of arrow A. Two other lamps

21 and 22 are positioned in alignment corresponding to the stem of the arrow. In like manner three lamps 23, 24 and 25 are arranged at the opposite end of the casing to illuminate the points of arrow B, lamps 26 and 27 serving to light up the stem of said arrow. The tail lamp 28 is centrally positioned opposite the opening T. The several lamps are connected by electric conductors with each other and with a plurality of terminal posts 29, 30, 31 and 32 projecting beyond the bottom of the casing. The casing bottom is formed with an opening 33 having upwardly flaring sides terminating in an opening 34 adjacent the tail lamp 28. A circular partition or wall 35 surrounds the tail lamp 28 to shield its light from the adjacent arrow openings, but a break is provided in wall 35 opposite to and communicating with the opening 34 and flared opening 33. It will be seen from the foregoing description that a license number suspended at the bottom of the casing 5 will receive a downwardly directed light from the tail lamp 28. Small circular partitions 36 and 37 are carried on either side of the central partition 35 being so positioned as to shield the arrow openings A and B from lamps 21 and 26 respectively. The purpose of these partitions will be more fully set forth.

The switch box 38 comprises a bottom or rear plate 39, a front or cover plate 40 and an interposed block 41 of insulating material. A pair of plates 42 and 43 formed of conducting material are secured to the bottom plate 39 below the insulation block 41. The block 41 is formed with a segmental piece cut out to provide a V-shaped opening 44 in which is mounted an operating handle 45 being pivotally secured at its inner end by a pin 46, the ends of which engage with circular recesses formed in the cover and bottom plates respectively. The operating handle 45 comprises a metal hub member 47 and a V-shaped extension 48 integral therewith of substantially inverted U cross section. A block 49 has its tapered end pivoted by a horizontal pin 50 in the inner part of the extension or holder 48, while its for-

ward end extends therefrom and terminates in the handle 51. A guide plate 52 extends across the forward edge of the V-shaped recess 44 in the insulating block 41 and is provided with a series of holes 53 with which a lug 54, carried on the upper surface of extension 48, is adapted to successively engage. A pair of spring tongues 55 are connected by ears 56 with the respective plates 42 and 43. These tongues extend along the sides of the V-shaped recess 44 for a portion of their length and terminate in spring contact members 57 normally projecting in the path of movement of the handle holder 48. The ends of these contact members are bent outwardly and are adapted to enter recesses at the forward edges of the V-shaped recess 44 and contact with other bent contact members 58 contained therein. The pivoted block 49 within the metal holder 48 carries a pair of depending contact members 59 adapted when the handle 51 is depressed to contact with the lower plates 42 and 43. Pockets 60 and 61 are formed in the upper face of the insulating block 41 in which small electric lamps 62 and 63 are located. The top cover plate of the switch box is provided with a plate 64 extending across these pockets and provided with cut out arrows *a* and *b* similar in disposition to the arrows A and B on the signal casing 5. A series of terminals 65, 66, 67, 68 and 69 are provided at the rear of the insulating block 41. Terminal 65 is electrically connected by a contact piece 70 with plate 42; terminal 66 is connected by a wire 71 with the handle extension 48; terminal 67 is connected by wires 72 with the lamps 62 and 63; terminal 68 is connected by contact piece 73 with plate 43; and terminal 69 is connected by wires 74 with contacts 58.

Referring now to the diagrammatic view of the electrical connections shown in Fig. 2 a wire 75 is connected at one end to terminal 65 and at its opposite end to lamp 22. The wire 75 however is intercepted by a second conductor 76 which in turn is connected electrically with lamps 18, 19, 20 and 26. From terminal 66 a wire 77 extends and is joined to a wire 78, connecting one side of a battery B with one of the terminals of a switch 79. A wire 80 connected with wire 78 connects with one post of a switch 81 controlling the tail lamp. From terminal 67 an electric wire 82 extends to the casing and serves as the return conductor for the several lead wires. This wire is connected by a branch wire 83 leading to the opposite side of battery B. Terminal 68 is connected by a main conductor 84 which leads to lamp 27, and is provided with a branch conductor 85 leading to lamps 21, 23, 24 and 25. Terminal 69 is connected by a wire 86 with a conductor 87 which leads from the opposite

side of switch 79 to one terminal on a horn 88, the other terminal of which is connected by a wire 89 to wire 83 and thence to battery B. The opposite terminal of switch 81 is connected by a wire 90, with the tail light 28. In giving the preceding electrical connections it will be understood that the several wires leading to the lamps in the signal casing are merely lead lines conducting the current to the different lamps; the wire 82 is used as a common return wire for closing the circuit in each instance.

From the foregoing description the operation of the device will be readily understood. The tail light 28 which is centrally located between the arrows A and B is adapted to be lighted at night and to remain lighted all the time the machine is in use. The switch 81 controls this light and current is supplied thereto by means of the wires 80 and 78 which connect with one side of the battery B with wire 90 which leads directly to the lamp 28 and the return wires 82 and 83 returning the circuit to the other side of battery B.

Assuming now that the machine is about to turn to the left the handle 51 being in its central position as shown in Fig. 2 is moved to the left until the metal handle holder 48 contacts with the spring contact 55 whereupon the three lights 18, 19 and 20 at the points of the arrow A will become illuminated together with lamps 22 and 26. It will thus be seen that an arrow in the signaling surfaces on the opposite sides of the casing 5 will be illuminated and that the stem of this arrow will be represented by the lamps 22 and 26 in addition to the tail lamp 28 which is in the same horizontal alignment and which is always burning. The electric circuits and the passage of the current for this operation are as follows: The central metal handle holder 48 is connected through wires 77 and 78 to one side of the battery B. When this holder contacts with the spring contact member 55 the current passes through plate 42 and by means of its electrical connection with terminal 65 the current is conducted along wire 75 directly to lamp 22 and by means of the wire 76 to lamps 18, 19, 20 and 26. The handle remains in this position until the machine again resumes a straight path when the handle is turned to its central position and the lights 18, 19, 20, 22 and 26 are extinguished. In order to provide an additional signal or to attract the attention of the driver of a following machine to the fact that a signal is being made, the horn 88 can be sounded by simply pushing the handle 51 to its extreme left hand position when the end of spring contact 56 will be brought into contact with 58 and the horn sounded. The current in this instance

passes as before from the battery through the central handle holder 48, thence through contact member 58 leaving the terminal 69, thence through conductor 86, wire 87 to the 5 horn 88 from whence the current is returned to the battery B by way of conductors 89 and 83, thus an additional use of the horn is provided for in conjunction with the operation of the light signal and the arrangement is such that but a single lever is necessary to perform both operations.

The horn may be operated independently of the controlling lever 51 by operating switch 79 whereupon a circuit is established 15 through wires 87, 78, battery B and wires 83 and 89.

If it is desired to indicate that the machine is about to turn to the right the handle 20 51 is moved to the right sufficiently to cause the metal holder 48 to come in contact with the spring 56 whereupon lamps 23, 24, 25, 27 and 21 will be illuminated to light up arrow B and the stem extending through and including the tail light 28 and lamp 21. 25 The current in this instance is caused to pass through handle holder 48, contact member 56 leaving the switch box at terminal 68 from whence it is conducted to the lamp 27 directly by the wire 84 and by branch 30 wire 85 to lamps 21, 27, 23, 24 and 25. A further movement of the handle 51 to the right will cause the contact member 56 to abut against the contact 58 whereupon the horn 88 will be sounded in exactly the same 35 manner as referred to when the signal was described as indicating a turn to the left.

Should the driver wish to indicate that the machine was about to stop, assuming the parts to be in the position shown in Fig. 2 40 it will only be necessary to press the handle 51 so as to cause it to move downwardly about the pivot pin 50 until the contact members 59 come in contact with the plates 42 and 43. This will result in the illumination 45 of all of the lights in the heads and stems of the arrows A B.

The small lamps 62 and 63 located in pockets formed in the insulating block will be illuminated either one at a time or both 50 together, simultaneously with the corresponding movement of the controlling handle 51 and will thus indicate by lighting up the arrow openings formed in the cover of switch box 38 whether or not the lights 55 of the main signal are operating successfully. The circuits for these auxiliary lamps 62 and 63 are formed by means of the handle causing a contact with either the plate 42 or 43 or both the return circuit being conducted from terminal 67 by wires 82 and 83 to a battery B.

It will thus be seen that by means of our improved apparatus a visible signal is flashed which will indicate to an approach-

ing or a following machine the direction 65 about to be taken by the car on which the signal is carried. In addition to the flash of light an audible signal is provided adapted to be sounded simultaneously with the light of the visible signal. A further advantage which the present invention possesses is the provision of a miniature signal corresponding to the illuminated signal and located at the switch box to indicate to the operator that the main signal is or is not 70 75 working successfully.

Having described our invention what we claim is:

1. A switch including a casing, an insulating block located in said casing and provided 80 with a recess, a set of contacts carried by said block, an arm pivotally mounted upon the latter and adapted to move laterally within the recess to alternately engage the contacts of said set, other contacts mounted 85 upon the base of the casing and a member pivotally mounted on the said arm and equipped with contacts adapted to engage the contacts supported by the said base.

2. A switch including a casing, an insulating block located in said casing and provided with a recess, two sets of contacts carried by the said block, an arm pivotally mounted upon the latter and adapted to move within the recess to engage one of said sets of contacts and to also force the latter into engagement with the other set of contacts, other contacts mounted upon the base of the casing and a member movably mounted on said arm and equipped with contacts adapted to engage the contacts supported by the said base for the purpose set forth.

3. A switch comprising a block having a recess, a contact in said block at each side of said recess, a spring contact adapted to engage each of the first named contacts, an arm pivotally mounted in the block, positioned within the recess and adapted to move laterally therein to engage said spring contacts and to force the latter into engagement with 105 said first named contacts, contacts on said block extending over said recess, a member pivotally mounted in said arm and adapted to engage the last named contacts at any time.

4. A switch comprising a block having a recess, a contact in said block at each side of the recess, contacts on said block extending over said recess, an arm pivotally mounted in the block, positioned within the recess 120 and adapted to be moved laterally therein to engage the first named contacts, and a member pivotally mounted in the arm and adapted to engage said extending contacts.

5. A switch comprising a block, an arm 125 pivotally connected with the block and adapted to swing relatively thereto, a contact on the block at each end of the path

of movement of the arm and adapted to be engaged thereby, a member pivoted in the arm and adapted to swing in a plane vertical to the path of movement of the arm, con-
5 tacts on the block in a plane parallel to the path of movement of the arm adapted to be engaged by said pivoted member.

In testimony whereof we affix our signatures in presence of two witnesses.
